[57] CLAIM

The ornamental design for a marking instrument, as shown and described.

DESCRIPTION

FIG. 1 is a right side elevational view of a marking instrument showing my new design in an exploded condition, the left side being a mirror image thereof; FIG. 2 is a top, right front perspective view with the cap member in place;

FIG. 3 is a front elevational view of the cap member with the writing instrument body removed for convenience of illustration;

FIG. 4 is a top plan view of FIG. 2; and,

FIG. 5 is a bottom plan view of FIG. 2.

The FIG. 2 view has been drawn to a reduced scale with respect to FIG. 1, and FIGS. 3 through 5.
